UNITED STATES PATENT OFFICE.

GEORGE PRIFOLD, OF LINWOOD, PENNSYLVANIA, ASSIGNOR, BY MESNE ASSIGNMENTS, TO UNITED ROOFING & MANUFACTURING COMPANY (DEPARTMENT OF BARRETT MANUFACTURING COMPANY), OF WILMINGTON, DELAWARE, A CORPORATION OF DELAWARE.

BLOCK-PRINTING MACHINE.

1,204,312.

Specification of Letters Patent. Patented Nov. 7, 1916.

Application filed November 17, 1915. Serial No. 62,007.

To all whom it may concern:

Be it known that I, GEORGE PRIFOLD, a citizen of the United States, and a resident of Linwood, county of Delaware, State of Pennsylvania, have invented certain Improvements in Block-Printing Machines, of which the following is a specification.

My invention relates to certain improvements in block printing machines for printing rugs and like materials.

The object of my invention is to improve the means for governing the several printing block carriers so that certain blocks will make an impression at a given time as dictated by the mechanism which is set for a given type, size, or color of rug, and which acts automatically to select the blocks as the material is fed through the machine.

In the accompanying drawings: Figure 1 is a side view of sufficient of a block printing machine to illustrate my invention; Fig. 2 is an enlarged view, partly in section, illustrating the action of one of the pin wheels; Fig. 3 is a plan view of a pin wheel taken on the line *a*—*a*, Fig. 2; Fig. 4 is a detached perspective view of the latch; Fig. 5 is a detached perspective view of one of the pins; and Fig. 6 is a view illustrating a modification.

Referring to the drawings, 1 is the frame of the machine having guides 2 arranged a given distance apart for the several carriers 3 on which the printing blocks 4 are mounted. On each carrier are rollers 5 with which the cams 6 engage which raise the carriers and allow them to descend so that the block can make an impression. The cams 6 are mounted on transverse shafts 7 driven in any suitable manner from a power shaft at one end of the machine. In the present instance, a longitudinal shaft 9 is geared to the power shaft and to the several cam shafts 7.

10, 10 are weighted latches for holding the printing block carriers out of action. These latches are pivoted to the main frame and engage portions 11 of the carriers, as shown. The lifting cam 6 for the carriers each have a raised portion 8, which lifts the carrier higher than the engaging portion of the latch so as to allow the latch to swing under the portion 11 of the carrier and also

to allow the latch to be withdrawn when the block is to make an impression.

Loosely mounted on each cam shaft 7 is 55 a pin wheel 13, and in the present instance, on the hub of this wheel are two sprocket wheels 12. In the rim of the pin wheel is a series of threaded openings for the releasing pins 14, which engage a projection 15 on 60 the latch 10. In the present instance, each pin is made as shown in Fig. 5 and has a threaded shank adapted to the threaded opening in the wheel 13. The mechanism is so timed that a pin 14 will strike the latch 65 when the high portion 8 of the lifting cam 6 is in contact with the roller 5 and, as the cam turns, the portion 11 of the carrier drops below the latch and the carrier follows the cam until the block makes an impression, 70 when it is again raised by the cam and as the high portion comes under the roller the weighted latch will swing into engagement with the portion 11 of the carrier until it is again released.

16, 16 are the drive chains adapted to the sprocket wheels, as shown, so that the pin wheels will turn in unison. On a driving shaft 19 is a sprocket wheel 18 around which passes a chain 20 from a sprocket wheel 17 on the hub of the pin wheel of the first printing section. Other means of driving the pin wheels may be adopted, if desired, and, in Fig. 6, I have illustrated a longitudinal driving shaft 16^a geared to the pin 85 wheel 13.

In operation, the fabric, or other material, to be printed is fed intermittently through the machine in the ordinary manner, the amount of the feed being equal to the width 90 of the face of the printing blocks. The pins 14 are set on their wheels 13 so that certain of the blocks will be released and will make the impression at a given time, according to the size of the rug and the number 95 of colors used.

When a fixed pattern is being printed the pins may be formed integral with the wheel and they may be located on the periphery, as shown, or at the side, if desired.

I claim:

1. The combination in a block printing machine, of a frame; a series of block carriers thereon; means for reciprocating the

block carriers; a latch for each carrier to hold it out of action; a wheel mounted at each carrier for actuating the latch, said wheel having a pin arranged to engage the latch and to move it out of engagement with the carrier; and means for driving the several wheels.

2. The combination in a block printing machine, of a frame; a series of printing block carriers; a cam shaft and cams for

each carrier; a sprocket wheel and connected pin wheel loose on each shaft, one or more pins on the wheels; a latch for holding each carrier out of action, said latch being in the path of one of the pin wheels which is arranged to move the latch away from the carrier; and chains for driving the several sprocket wheels and pin wheels in unison. 15

GEORGE PRIFOLD.

Copies of this patent may be obtained for five cents each, by addressing the "Commissioner of Patents, Washington, D. C."
